UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

MANUAL AIR-FEED CONTROL FOR ROCK DRILLS.

Application filed November 29, 1921. Serial No. 518,551.

To all whom it may concern:

Be it known that I, LEWIS C. BAYLES, a citizen of the United States, and a resident of Easton, Northampton County, State of Pennsylvania, have invented a certain Manual Air-Feed Control for Rock Drills, of which the following is a specification, accompanied by drawings.

This invention relates to fluid pressure operated rock drills of the hammer type, but more particularly to air feed control for the feeding element of a stope drill, to enable the operator to maintain full rotation and hammer power with reduced air feed when going through a soft spot for instance.

A device of similar type is disclosed in the co-pending application of Fred M. Slater, Serial No. 398,387, filed July 23rd, 1920, the said application having matured into Patent No. 1,407,591 and assigned to Ingersoll-Rand Company. The primary object of the present invention is to enable the control of the feeding element of air feed cylinder to be effected by a simple pressure of the fingers or thumb upon a manual lever mounted on the drill handle ordinarily called the rotation handle. Instead of relying upon the pressure of the fingers or thumb upon a button, I provide a lever having substantial length and surface which may be grasped by the hand or fingers and enable sufficient pressure to be quickly brought upon the controlling valve to readily overcome the opposing air pressure within the handle tending to close the valve.

Further objects of the invention will hereinafter appear and to all of these ends the invention consists of the device and features of construction shown in the accompanying drawings in which—

Figure 1 is a side elevation partly in vertical section of a stope drill embodying the invention;

Figure 2 is an enlarged detail horizontal section partly broken away through the handle and controlling valve; and

Figure 3 is an enlarged detail vertical section through the vertical portion of a handle showing a modified form of controlling device.

Referring to the drawings, a stope drill is illustrated in Figure 1 having the usual cylinder A and front head B carrying the drill steel C. The front head is connected to the cylinder as by means of the usual side bolts

D. The cylinder A and its operative parts comprise the percussive element of the tool for imparting the impact blows of the piston hammer to the drill steel. The drill steel may be rotated by any suitable means, in this instance a machine of the independent rotation type being illustrated having the rotation motor casing E formed in the back end portion of the machine.

The feeding element comprises the usual air feed cylinder F having the piston G and the piston rod H provided with the rock engaging point J. Between the back end portion E and the air feed cylinder F is located the head block K, and the cylinder A, back end portion E, head block K and air feed cylinder F are held together as by means of the through bolts L.

Motive fluid is admitted to the percussive and feeding elements of the machine through the inlet O controlled by the throttle P in the head block K. The head block is provided with a handle P' for the machine, usually called the rotation handle, although this handle could be connected as desired to any suitable portion of the casing of the machine. In this instance, the handle P' is provided with the downward extension Q forming a convenient portion to be grasped by the hand of the operator.

In accordance with my invention, instead of controlling the air feed in the usual manner, as by means of the throttle valve P, I provide a valve R in the handle controlling ports and passages leading to the feeding element, thereby enabling the operator to regulate the feeding element in accordance with the requirements of the work without removing his hand from the handle.

In this instance, the handle is preferably hollow and provided with the passage S extending from a port T at the inner end of the handle to a valve chamber U near the handle extension Q. The valve chamber U communicates with the atmosphere through the end of the handle by means of the port V and the chamber is closed by means of the screw threaded plug W between which and the valve R a spring X is compressed so that the valve R normally closes communication between the chamber U and the atmospheric port V. The valve is preferably provided with a head or button Y at its outer end, in this instance extending through a sleeve Z secured over the handle P'. The sleeve Z is

in this instance provided with a hand lever *a* pivoted to the sleeve on the transverse pivot pin *b* and said lever extends over the valve head or button *Y* so that by pressing 5 the hand lever *a* towards the handle *P'* sufficient leverage is brought to bear upon the valve head to force the valve inwardly against the spring *X* and against air pressure from the feeding element tending to 10 hold the valve to its seat. The lever *a* is preferably provided with a beveled portion *b'* forming a stop for limiting the outward movement of the lever.

In the modification shown in Figure 3, the 15 handle extension *Q'* forming an extension of the handle *P'* having the passage *S*, is provided with the valve chamber *c*, and the valve *d* controls communication between the chamber *c* and the port *e* leading to atmosphere 20 through the end of the handle extension *Q'*. The valve *d* is conveniently mounted in a valve cage or block *f* and is normally pressed to its seat by the spring *g*. A sleeve *h* over the handle extension holds 25 the valve plug *f* in position and the valve head *j* extends through this sleeve in position to be actuated by the hand lever *k* which in this instance, is pivoted at one end at one side of the valve on the transverse 30 pivot pin *o* and is provided at the other end at the other side of the valve with a bearing portion *p* extending into the interior of the handle extension *Q'* and having a spring *r* interposed between the portion *p* and the 35 wall of the handle extension *Q'*. A stop *s* extends longitudinally from the end of the hand lever adjacent the pivot *o* and cooperates with the body portion of the handle to limit the outward movement of the hand 40 lever *k*.

The modified construction shown in Figure 3 affords a longer grip for the hand of

the operator as illustrated, and enables the controlling valve to be readily manipulated when located in the handle extension *Q'* although it is to be understood that if desired, either form of the device shown in Figures 2 and 3 may be located either in the handle portion or the handle extension of the machine. 45

I claim:

1. In a rock drill the combination with a fluid pressure feeding element, and a rotation handle, extending at one side of the machine, of ports and passages permitting the 55 passage of motive fluid from the feeding element through the handle to atmosphere, a normally closed spring pressed valve located in the handle controlling said passage of motive fluid to atmosphere, and a pivoted lever having a manual portion extending longitudinally along the handle and cooperating with the valve for operating the valve. 60

2. In a rock drill the combination with a fluid pressure feeding element, and a rotation handle extending at one side of the machine, of ports and passages permitting the 65 passage of motive fluid from the feeding element through the handle to atmosphere, a manually closed spring pressed valve located in the handle controlling said passage 70 of motive fluid to atmosphere, and a lever having a manual portion extending longitudinally along the handle and cooperating 75 with the valve, one end of said lever being pivoted transversely to the handle at one side of the valve, and a spring on the handle beneath the opposite end of the lever assisting the valve spring to force the handle outwardly away from the handle. 80

In testimony whereof I have signed this specification.

LEWIS C. BAYLES.
